UNITED STATES PATENT OFFICE.

HARLEY E. ANDERSON, OF CHICAGO, ILLINOIS, ASSIGNOR TO C. H. BOSWORTH, CHARLES B. MOORE, C. A. CARSCADIN, AND JOHN H. S. LEE, COPARTNERS DOING BUSINESS UNDER THE FIRM NAME OF BOSWORTH, MOORE & CARSCADIN.

APPARATUS FOR MANIPULATING BRAKES.

Application filed August 5, 1921. Serial No. 490,080.

To all whom it may concern:

Be it known that I, HARLEY E. ANDERSON, a citizen of the United States, residing at Chicago, in the county of Cook and State of Illinois, have invented certain new and useful Improvements in Apparatus for Manipulating Brakes, of which the following is a specification.

My invention relates to apparatus operable by hand for setting and releasing the brakes of a railway car, the invention being concerned more particularly with a brake operating apparatus of the type employing a hand lever which, with its associated mechanism, sets the brakes by giving an upward pull on a rod, or equivalent element on the outside of the car, which upward pull is transmitted by suitable devices into a substantially horizontal pull on the brake beams. An apparatus of this sort may be used to great advantage on a freight car in place of the usual brake staff and hand wheel since it is capable of being manipulated more conveniently and safely, is more certain in its operation, affords a quicker take-up of the slack in the brake connections, and can be constructed to apply a very considerable braking force to the wheels of the car without undue exertion on the part of the trainman.

One of the principal objects of the present invention is to provide, in a brake apparatus of the type indicated, an improved lever actuated mechanism for applying power to the brake connections (especially to the substantially vertically disposed pull rod on the outside of the car) which can be operated in setting and releasing the brakes, conveniently, safely, effectively and with a minimum of exertion on the part of the trainman; and which consists of a few simple parts of strong and durable construction so that the cost of manufacture, installation and up-keep will be relatively low.

It is another object to provide such a construction so arranged that the brake can be readily actuated by hand when desired, and to arrange the parts in such a manner that substantially a full stroke of the operating lever shall be available for such installation quite regardless of the wear upon the parts.

The invention contemplates the use of a bell crank or rocking member which pivots

on a fixed axis, although in its broader aspect the invention is not limited to a transmission element of this description. The invention, however, provides, for use in this connection, a bell crank which is pivotally mounted on the car without use of a separate pin or bolt which, if employed, is likely to become detached or broken, or may be lost when the parts are disassembled for repair.

The invention consists in the new and improved constructions, arrangements and devices to be hereinafter described and claimed for carrying out the above stated objects and such other incidental objects as will be mentioned in the following description of a preferred embodiment of the invention.

The invention is illustrated in the accompanying drawings, wherein—

Fig. 1 is a side elevation of the apparatus shown as applied to the end of a box car.

Fig. 2 is another view, in elevation, but taken from a point at 90° from the point of view of Fig. 1.

Fig. 3 is a fragmentary detail view of the rack for operating the pull rod.

Fig. 4 is a sectional plan on line 4—4 of Fig. 2.

Fig. 5 is a sectional plan on line 5—5 of Fig. 6.

Fig. 6 is a sectional plan on line 6—6 of Fig. 5.

Fig. 7 is a view, in perspective, of the detent for holding the rack in its elevated position.

Fig. 8 is a similar view of the tripping device associated with the detent.

Fig. 9 is a sectional view, on line 9—9 of Fig. 5 but showing only the housing, the detent and the trip being omitted.

Fig. 10 is a side elevation, with parts in section, to illustrate the construction of the bell crank and the means for mounting the same on the car.

Fig. 11 is a sectional view on line 11—11 of Fig. 10.

Fig. 12 is a fragmentary view, in perspective, of a portion of the bell crank.

Fig. 13 is an inverted plan view of the casting by means of which the bell crank is mounted on the car, and

Fig. 14 is a sectional view on line 14—14 of Fig. 13.

The brake operating apparatus is shown

in the drawings as installed against the end wall of a railway box car, the power applying or lifting mechanism being arranged obliquely with respect to the end of the car 5 (as shown particularly in Fig. 5) for convenience in manipulating the lever.

10 designates a chain, or other flexible connection, which extends under the car body and is attached to and forms part of 10 the mechanism, hereinafter referred to as the brake rigging, for applying the brake shoes to the wheels of the car. 11 is a bell crank pivotally mounted, as will be hereinafter described, on the under side of the 15 car body and formed with an integral hook 12 to which chain 10 is engaged in the manner described and claimed in my co-pending application Serial No. 490,079 filed August 5, 1921; the bell crank being formed with 20 a curved, preferably grooved portion 13 over which the chain is flexed when the bell crank is rocked. 14 is a pull rod engaged with a rack 15 and formed at its lower end with a clevis 16 secured by a pin 17 to the 25 bell crank 11. The bell crank changes the vertical movement of pull rod 14 to a substantially horizontal pull on the chain 10.

While the transmission device as above described is preferred in this connection, 30 any other suitable means might be employed for transmitting power from the pull rod to the chain, or its equivalent, such, for example, as that shown in my copending application referred to.

35 The rack 15 extends into a housing 18 formed with obliquely arranged ears 19 for attaching the housing to the end sheathing 20 of the car. The housing 18 is closed on the top except for an opening 21 through 40 which the rack 15 projects when raised, the rack being formed with a head 22 which substantially closes opening 21 when the rack is in its lower or normal position. The housing is formed on one side with a slot 45 23 and opposite said slot with an interior web 24 formed with a vertical slot 25. 26 is a hand lever formed with a stud, the middle portion 27 of which is square in cross section and has fixed thereto a mutilated 50 pinion 28, that is to say, a pinion having teeth 29 on a portion only of its circumference. In the normal or vertical position of the lever 26 the teeth 29 are at the bottom of the pinion and out of engagement with 55 the teeth 30 of rack 15. The pivot stud 27 on the lever is formed with a journal 31 which lies within and has a diameter slightly less than the width of slot 23. At the other side of pinion 28 the lever stud is formed 60 with a journal 32 adapted to fit the slot 25. The end of the stud remote from the lever 26 is formed with a retaining head 33 lying within an offset portion 34 of the housing and bearing against web 24. The slots 23, 65 25 are arcuate at the bottom providing bear-

ings for journals 31, 32. The upper end of slot 25 is formed with a circular enlargement 35 having a diameter slightly larger than head 33 through which the head of the pivot stud is passed in assembling the mechanism. 70 The rack 15 is formed on the side opposite from teeth 30 with a series of holding teeth 36 and the adjacent portion of the housing 18 is formed with an offset 37 in which is arranged a detent 38 having a tooth 39 75 adapted to engage the holding teeth 36 on the rack. The under surface 40 of the tooth 39 is oblique and normally bears against the oblique surface 41 of the upper holding tooth on rack 15. The offset portion 37 of the 80 housing is formed interiorly with bearings 42 for arcuate webs 43 on the lower end of detent 38. The tail piece 44 of the detent projects out through an opening 45 in the housing and is normally engaged by a lug 46 formed on the trip member 47. The latter is pivoted by means of a pin 48 between a pair of arms 49, 49 projecting outwardly from the housing. The trip is formed at its outer portion with a weight 50. The body 90 of detent 38 lies within a narrowed portion 51 of offset 37. The webs 43 on the detent 38 are formed with lugs 52 which are adapted to be engaged by lugs 53 on the rack 15 when the latter drops from a raised position to its normal position. This engagement of lugs 53 with lugs 52 automatically returns the detent 38 to its operative position from which it has been moved by reversing the 95 position of trip 47 when the brakes are released. The lever 26 is provided with an extension plate 54 which, in the normal position of the lever, covers slot 23. 100 The channel portion 13 of the bell crank, which receives the chain 10 when the bell 105 crank is rocked to take up slack in the brake connections, is preferably formed, as best shown in Fig. 10, on a curve which is eccentric with reference to the pivotal axis of the bell crank. That is to say, the surface 110 over which the chain is flexed approaches such pivotal axis from the point of engagement of the chain with hook 12. This results in effectively shortening the lever arm of the bell crank which produces the pull upon the 115 chain as the bell crank is rocked in the operation of applying the brakes. During the first part of the movement of the bell crank the essential thing is to take up slack in the chain 10 and in the brake connections to 120 which the chain is attached as quickly as possible. But when the brake shoes have been brought against the wheels it is desirable to have the lever arm operating on the chain as short as possible so as to multiply 125 the power exerted through operation of the hand lever 26. The curvature of the portion 13 of the bell crank gives the desired quick take-up and multiplied power at the time the brakes are being set. 130

Fig. 4 illustrates the preferred arrangement for engaging the pull rod 14 with rack 15. The rack is formed at the bottom with a housing 55, the bottom 56 of which is formed with an obliquely arranged opening 57 conforming to the shape of a head 59 on the end of the pull rod. After the rod and rack have been assembled the rod is turned to engage its clevis 16 with the bell 10 crank and this turns the head 59 at substantially right angles to the opening 57.

The construction of the bell crank and casting on which it is mounted is illustrated in Figs. 10 to 14 inclusive. The bell crank 15 is formed with gudgeons 60, 60 adapted to bear against curbed surfaces 61 formed in the lower edges of a pair of spaced depending flanges 62 formed on a casting or bracket member 63 bolted, as indicated at 20 64, to the under side of the car body and formed preferably with a flange 65 overlapping the end of the car body. The flanges 62 are formed with inwardly projecting studs 66 forming a support for an 25 arcuate web 67 on the bell crank. This web is formed with a pair of notches 68 arranged so that the bell crank may be engaged with the bracket member 63 by placing the bell 30 crank in such position with respect to the bracket that notches 68 will register with the studs 66. This position of assembling and 35 disassembling is, of course, outside of the operative range of angular movement of the bell crank so that when the installation has been completed, disengagement of the bell crank from the bracket is impossible without disassembling the apparatus.

Operation: To set the brakes the trainman, who ordinarily stands on a platform (not 40 shown) on the end of the car, raises the lever 26, turning the same to the left as the parts of the apparatus are shown in Fig. 1. The teeth 29 on pinion 28 engage the teeth 30 on rack 15, raising the rack and exerting 45 a pull through rod 15 and bell crank 11 on the chain 10 forming part of the brake rigging on the underside of the car. Ordinarily it will require several oscillations of 50 the lever to take up the slack in the brake connections and set the brakes. The lever, in such case, may be raised as far as is found convenient. Its stroke may be short or long as the trainman prefers. Detent 38 which is held against the rack by engagement 55 of lug 46 with the tail piece 44 of the detent (Fig. 5) will engage the holding teeth on the rack as soon as the lever is released. When the lever is released, the pinion, in the backward rotation which 60 takes place because of the weight of the lever, will climb up rack 15 until the teeth 29 have passed out of mesh with the teeth 30 on the rack, whereupon the pinion and lever will drop to their normal position. 65 That is, the journals 31, 32 on the pivot stud

of the lever will slide downwardly in slots 23, 25 until they rest in the curved lower ends of the slots.

To release the brakes the trip 47 is reversed so that weight 50 bears against the upper side of the tail piece 44 of detent 38. This movement of the trip is not intended to disengage the detent from the holding teeth of the rack. In order to effect such disengagement, it is necessary to raise the 75 rack by an upward pull on lever 26 sufficiently to relieve the detent of the downward thrust imposed on it by the rack. As soon as the detent is relieved from this thrust the weight of the trip will throw the detent backwardly in the pocket 51 of the housing and the lever having been released by the trainman, the rack will fall to its normal position. At the end of the downward travel of the rack the lugs 53 thereon come into contact with the lugs 52 on 80 detent 38, and the detent is rocked back to its normal position, the force of the blow against the same being sufficient to return the trip 47 to its normal position. For indicating to the trainman the proper manipulation of the trip 47, the weight 50 of the trip device bears on its upper face the word "Set" in the position of the trip for 85 permitting continued operation of the detent 38. Upon the opposite face of the weight 50 of the trip device, which opposite face is uppermost when the trip is turned for causing the detent 38 to be thrown out of operation, I have provided 90 the word "Release," the words "Set" and "Release" being applied preferably by being cast directly upon the weight.

As will be readily understood, in the operation of the brake the trainman may take up the slack and bring the brakes into contact with the wheels by either short or long strokes of the lever 26. When the slack is all taken up, however, it is desirable that the lever 26 be then moved to the bottom of its operative stroke so as to bring the teeth 29 into engagement with the lowest possible teeth 30 of the rack. The trainman is then in position, by a single stroke, to bring the breaks into completely set condition, regardless of the amount of wear of the parts. If the trainman desires, as is very often the case, he may then throw the trip 47 into position for releasing the detent 38, leaving him then in complete control of the car, by hand. Under these circumstances, the trainman may apply just as much pressure as he desires upon the brakes, from the zero pressure of original contact when the slack is completely taken up, to the approximately full pressure of four to eight thousand pounds if desired. He can vary the pressure as desired to meet changing conditions of track, grade, etc., the only requirement being that he does not lower the lever 26

sufficiently to release the teeth 29 from the rack.

As is best shown in Fig. 5, a headed rivet 69 is preferably inserted in the housing 18 above the opening 35, after assembly is completed, for preventing the removal of the lever 26.

I do not claim as my invention the particular means shown in Figs. 10 to 14 inclusive for pivoting the bell crank to the car body; nor do I claim broadly the eccentric configuration of the portion of the bell crank over which the chain winds whereby the effective lever arm of the bell crank acting on the chain is shortened as the brake shoes approach the set position.

I claim:

1. In apparatus for manipulating the brakes of a railway car, the combination of a power transmission element movable in the direction of its length, and a lever oscillatable in a substantially vertical plane and provided with means which, when the lever is raised, engages directly with and moves the transmission element and, when the lever is released by the operator, is automatically disengaged from the transmission element.

2. In apparatus for manipulating the brakes of a railway car, the combination of a power transmission element movable in the direction of its length, a lever oscillatable in a substantially vertical plane and provided with means adapted, when the lever is raised, to engage and move the transmission element and, when the lever is released by the operator, automatically by the weight of the lever to be released from the transmission element, and means acting positively on the upward stroke of the lever to cause operative engagement of the lever with the transmission element.

3. In apparatus for manipulating the brakes of a railway car, the combination of a power transmission element movable in the direction of its length, and a lever oscillatable in a substantially vertical plane and provided with means which, when the lever is raised, engages directly with and moves the transmission element, and, when the lever is released by the operator, is automatically disengaged from the transmission element allowing the lever to return by gravity to its normal position.

4. In apparatus for manipulating the brakes of a railway car, the combination of a power transmission element movable in the direction of its length, and a lever oscillatable in a substantially vertical plane and provided with means which, when the lever is raised, is actuated positively for engaging and moving the transmission element and, when the lever is released by the operator, is automatically disengaged from the transmission element by the weight of the lever

allowing the lever to return by gravity to its normal position.

5. In apparatus for manipulating the brakes of a railway car, the combination of a power transmission element movable in the direction of its length and a lever provided with means for engaging and moving the transmission element when the lever is given an angular movement in one direction, said lever being mounted so that its pivot is movable along a path parallel with the transmission element to allow disengagement of the lever from the transmission element when the lever is given a movement in the direction opposite to that specified.

6. In apparatus for manipulating the brakes of a railway car, the combination of a vertically disposed transmission element movable in the direction of its length and a lever oscillatable in a substantially vertical plane with means for engaging and moving the transmission element when the lever is raised, said lever being mounted so that its pivot is movable along a path parallel with the transmission element to allow disengagement of the lever from the transmission element on the return movement of the lever.

7. In apparatus for manipulating the brakes of a railway car, the combination of a rack, a lever having fixed thereto a mutilated pinion adapted to engage said rack, and means for mounting the lever which permits a movement of its pivot parallel with said rack.

8. In apparatus for manipulating the brakes of a railway car, the combination of a substantially vertical rack, a lever adapted to be oscillated in a substantially vertical plane, a mutilated pinion fixed to said lever on its axis of oscillation, and means for mounting the lever which permits said pinion to move upwardly from its normal position in parallelism with the rack.

9. In apparatus for manipulating the brakes of a railway car, the combination of a housing, a vertically disposed rack extending into the housing, a lever provided with a substantially horizontal pivot stud projecting into the housing, guides for the pivot stud allowing substantially vertical movement thereof in the housing, and a mutilated pinion fixed to said stud.

10. In apparatus for manipulating the brakes of a railway car, the combination of a housing formed with a vertical slot, a vertically disposed rack extending into the housing, a lever provided with a substantially horizontal pivot stud projecting into the housing through said slot, guides for the pivot stud allowing substantially vertical movement thereof in the housing, a mutilated pinion fixed to said stud, and a plate on the lever adapted, in the normal position of the lever, to cover said slot.

11. In apparatus for manipulating the

brakes of a railway car, the combination of a housing, a vertically disposed rack extending into the housing, a lever provided with a substantially horizontal pivot stud projecting into the housing, guides for the pivot stud allowing substantially vertical movement thereof in the housing, a mutilated pinion fixed to said stud, said rack being formed with holding teeth, a detent in said housing to engage said teeth, and a trip adapted in one position to hold the detent in engagement with said teeth and in another position to disengage the detent from the teeth.

12. In apparatus for manipulating the brakes of a railway car, the combination of a housing, a vertically disposed rack extending into the housing, a lever provided with a substantially horizontal pivot stud projecting into the housing, guides for the pivot stud allowing substantially vertical movement thereof in the housing, a mutilated pinion fixed to said stud, said rack being formed with holding teeth, a detent in said housing to engage said teeth, a trip adapted in one position to hold the detent in engagement with said teeth and in another position to disengage the detent from the teeth, and a bearing formed in said housing having a rounded upper surface, the detent being formed with a rounded web to engage said bearing.

13. In apparatus for manipulating the brakes of a railway car, the combination of a housing formed with oppositely disposed vertical slots, a lever having a pivot stud formed with journals arranged in said slots, a vertical rack extending into the housing, and a mutilated pinion fixed to said pivot stud and adapted to engage said rack.

14. In apparatus for manipulating the brakes of a railway car, the combination of a housing formed with oppositely disposed vertical slots, a lever having a pivot stud formed with journals arranged in said slots, a vertical rack extending into the housing, and a mutilated pinion fixed to said pivot stud and adapted to engage said rack, the end of the pivot stud remote from the lever being formed with a retaining head and the slot adjacent thereto with an enlargement to admit the head when the parts of the mechanism are assembled.

15. In apparatus for manipulating the brakes of a railway car, the combination of a vertical rack, a lever oscillatable in a vertical plane having a pinion fixed thereto which is adapted to engage said rack when the lever is raised, and to be automatically disengaged therefrom when the lever is released.

16. In apparatus for manipulating the brakes of a railway car, the combination of a bell crank at the bottom of the car body, a connection from said bell crank to the

brake rigging, a vertically disposed pull rod connected with the bell crank, and a lever oscillatable in a vertical plane adapted, when raised, to engage directly with the pull rod and raise the same, and, when released, to be automatically disengaged from the pull rod and returned to its normal position by gravity.

17. In apparatus for manipulating the brakes of a railway car, the combination of a bell crank at the bottom of the car body, a connection from said bell crank to the brake rigging, a vertically disposed pull rod connected with the bell crank and provided with a rack, and a lever oscillatable in a vertical plane provided with a pinion adapted, when the lever is raised, to engage directly with said rack and, when the lever is released, to be automatically disengaged from the rack.

18. In apparatus for manipulating the brakes of a railway car, the combination of a bell crank at the bottom of the car body, a connection from said bell crank to the brake rigging, a vertically disposed pull rod connected with the bell crank, a lever oscillatable in a vertical plane adapted, when raised, to engage directly with the pull rod and raise the same, and, when released, to be automatically disengaged from the pull rod and returned to its normal position by gravity, and a detent device for holding the pull rod in its raised position.

19. In apparatus for manipulating the brakes of a railway car, the combination of a bell crank at the bottom of the car body, a chain connected with said bell crank and with the brake rigging, said bell crank being formed with a curved surface over which the chain is placed when the bell crank is rocked, a vertically disposed pull rod connected with the bell crank and provided with a rack, and a lever oscillatable in a vertical plane provided with a pinion adapted, when the lever is raised, to engage said rack and, when the lever is released, to be automatically disengaged from the rack.

20. In apparatus for manipulating the brakes of a railway car, the combination of a vertical rack, a housing for the upper end of the rack, the top of which is formed with an opening through which the rack extends when raised, the rack being formed with a cap piece which closes said opening when the rack is in its lowermost position.

21. In apparatus for manipulating the brakes of a railway car, the combination of a substantially vertical transmission element, a lever oscillatable in a substantially vertical plane which, when its outer end is raised, swings on a fixed axis and raises the transmission element and, when released, rises bodily to disengage the transmission element and is returned to its nor-

mal position by gravity, and releasable means for holding the transmission element at any elevated position.

22. In brake operating mechanism, the combination of a power applying device obliquely disposed on the car body, and comprising a substantially vertical rack formed at its lower end with a housing having an oblique slot in the bottom, a bell crank on the car oscillating in a plane longitudinal with respect to the car, and a pull rod adapted to be connected with the bell crank and having a head at its upper end which is adapted to pass through said slot and to stand at an angle thereto when the rod engages the bell crank.

23. In an apparatus for manipulating the brakes of a railway car, the combination of a member having a series of teeth movable in one direction for applying the brakes, a second member having a series of teeth adapted to mesh with said first named toothed member, a lever operatively connected with said second member adapted by alternate strokes in opposite directions to move said first named member alternately in the directions for tightening and loosening the brakes, and holding means adapted to be thrown alternatively into and out of operative position and adapted when in operative position to hold the first named member against movement upon the stroke of the lever in the direction for loosening the brakes, serving to cause the second toothed member to move out of mesh with said first named member, the arrangement being such that the lever is adapted to be brought to the beginning of its operative stroke, and the holding means then thrown out of operation, at the time when the brakes are first brought into contact with the wheels for the final effective stroke of the lever.

24. In an apparatus for manipulating the brakes of a railway car, the combination of a member having a series of teeth movable in one direction for applying the brakes, a second member having a series of teeth adapted to mesh with said first named toothed member, a lever operatively connected with said second member adapted by alternate strokes in opposite directions to move said first named member alternately in the directions for tightening and loosening the brakes, and holding means adapted to be thrown alternatively into and out of operative position and adapted when in operative position to hold the first named member against movement upon the stroke of the lever in the direction for loosening the brakes, serving to cause the second toothed member to move out of mesh with said first named member, the arrangement being such that at any time when the pressure is relieved from the holding means by

the lever such holding means can be thrown out of operation for a final actuating stroke of the lever.

25. In an apparatus for manipulating the brakes of a railway car, the combination of a member having a series of teeth movable in one direction for applying the brakes, a second member having a series of teeth adapted to mesh with said first named toothed member, a lever operatively connected with said second member adapted by a stroke in one direction to move said first named member for applying the brakes, releasable means for holding said first named toothed member against movement in the direction for releasing the brakes whereby said lever upon a stroke in the direction for releasing the brakes serves to move said second named toothed member out of mesh with said first named toothed member, and movable means adapted in one position to retain said releasable holding means in operative position and adapted in another position to move said releasable holding means out of operative position.

26. In an apparatus for manipulating the brakes of a railway car, the combination of a member having a series of teeth movable in one direction for applying the brakes, a second member having a series of teeth adapted to mesh with said first named toothed member, a lever operatively connected with said second member adapted by a stroke in one direction to move said first named member for applying the brakes, releasable means for holding said first named toothed member against movement in the direction for releasing the brakes whereby said lever upon a stroke in the direction for releasing the brakes serves to move said second named toothed member out of mesh with said first named toothed member, movable means adapted in one position to retain said releasable holding means in operative position and adapted in another position to move said releasable holding means out of operative position, and means adapted upon the complete brake loosening movement of the first named toothed member to give said movable means a movement into position to permit operation of said releasable holding means.

27. In an apparatus for manipulating the brakes of a railway car, the combination of a member having a series of teeth movable in one direction for applying the brakes, a second member having a series of teeth adapted to mesh with said first named toothed member, a lever operatively connected with said second member adapted by a stroke in one direction to move said first named member for applying the brakes, a detent for holding said first named toothed member against movement in the direction for releasing the brakes whereby said lever

upon a stroke in the direction for releasing the brakes serves to move said second named toothed member out of mesh with said first named toothed member, a trip device adapted in one position to retain the detent in operative position and adapted in another position to move the detent out of operative

position, and means adapted upon the complete brake loosening movement of the first named toothed member to give said trip a movement into position to permit said detent to operate upon the subsequent tightening of the brakes.

HARLEY E. ANDERSON.
